United States Patent Office.

DANIEL SNELL, OF LITTLE FALLS, NEW YORK.

Letters Patent No. 95,739, dated October 12, 1869.

IMPROVEMENT IN PERMUTATION-LOCKS.

The Schedule referred to in these Letters Patent and making part of the same.

To all whom it may concern:

Be it known that I, DANIEL SNELL, of Little Falls, in the county of Herkimer, and State of New York, have invented certain new and useful Improvements in Safe or Vault-Locks; and I do hereby declare the following to be a full, clear, and exact description of the construction and operation of the same, reference being had to the accompanying drawings, making a part of this specification, in which—

Figure 1 represents, in perspective, an external view of the lock in question.

Figure 2 represents a section through the lock.

Figure 3 represents, in perspective, the lock-bolt detached from the side-pieces of the lock.

Figure 4 represents, in perspective, one of the knobs of the lock removed therefrom, to better show its form and construction.

Figure 5 represents, in perspective, and as removed from the lock, the hubbed rings or tumblers used in the lock.

Similar letters of reference, where they occur in the separate figures, denote like parts in all of the drawings.

My invention relates, first, to a lock, in which the bolt and its side-plates are of uniform, or nearly so, size, so that the lock may be the door of the vault or safe, or a part of the door, and hinged or pivoted to it; and

My invention further relates to a lock, in which the bolt is held or controlled by two or more independent locking-devices, both of which must be actuated before the bolt can be moved; and

My invention further relates to a lock, in which the knob or knobs serve as knobs and key both, and in connection with which the tumblers act by permutation, and in which tumblers there are false depressions or openings for the bolt, or a projection thereon, to take into and thus mislead the person attempting to pick the lock or complicate the attempt at finding the wards and tumblers by machinery, as is now done.

To enable others skilled in the art to make and use my invention, I will proceed to describe the same, with reference to the drawings.

A represents the lock as partially swung out of the frame B, by which arrangement the lock serves as a door; but the lock may be set in a door, which door and lock could swing together in the ordinary way.

The lock is composed of three plates, *a b c*, of uniform, or nearly so, size. The outside plates *a c* are firmly united together, and the central plate *b*, which is the lock-bolt, moves between the side-plates or cheeks *a c*.

These plates lie close together, side by side, so that powder, or other explosive material, cannot be worked in between them, and they are so thick and solid that they cannot be damaged or disarranged.

These three plates *a b c*, two rigid and one movable, may be said to constitute the lock, the other features of it being the appliances by which the movable plate *b* is locked to the side-plates, or moved between them.

C D are knobs, secured to the side-plates *a c*, so that they cannot be drawn out, or driven in, and they may be thick enough and hard enough to prevent their being sawed off, except with great labor and much time.

On these knobs, there is a ring, *d*, having letters, figures, or characters thereon; and this ring, by means of a tooth or cog, *e*, on its interior perimeter, and the series of notches *f* on the knob, may be changed and set at pleasure.

The knobs, or, rather, their shanks *g*, pass through hubbed rings or disks, or what may be termed tumblers, *h h*, of which there may be one, two, three, four, or more.

In the drawings, I have shown but two hubs, *i i*, each of which has its flange or disk *j j*, while, in connection with the knob D, there is a ring, *k*, interposed between the flanges, in which ring there is a pin, *m*, that may be set into any one of the series of holes, *l*, in the under flange, so as to change the letters, or characters, or combinations, when desired to do so.

On the flanges that are visible, letters, characters, or marks are made, by the proper arrangement of which the tumblers are set, to allow the bolt to be moved, and the disarrangement of which locks the bolt.

This combination of letters simply for designating an arrangement of tumblers, or a disarrangement of them, has been used in various ways, and is well understood, and need not be elaborated further than to explain the mechanical devices that they are placed on.

In the shank of the knob D are formed, first, a recess, *n*, into which, when the knob or knobs are properly turned, the lock-bolt *b* may pass; second, a slot, *o*, into which the sub-bolt *p*, on the regular bolt, may move or enter; and, thirdly, a series of false holes, *q*, into which the sub-bolt *p* may move a short distance, but not far enough to allow the real bolt to be unlocked, while this small movement would defeat the finding of the true movement, by what is known as the "clock-work" system of finding the interior arrangement of a lock.

The bolt proper, *b*, has openings, *r r*, &c., through it long enough to allow it to slide past the screws that pass through them, and hold the outside plates together. It has also grooves, *s s s*, in it, into which tongues, *u*, of which there are three, but one only seen in the section on one of the face or cheek-plates, enter openings *t t*, through which the shanks of the knobs pass, the latter, *t*, being oblong, so that the bolt may slip past the shank of the knob D, which turns, but does not slide, while the other knob C and its shank not only turn, but slide with the bolt *b*,

though they can only slide when they are in the precise proper position to do so, and which position the combination of letters only can designate, and that the exact combination.

The shank of the knob C has a recess, *v*, in it, which will just receive the central one of the tongues *u* on the cheek-plate, when exactly opposite to it, and the tumblers and their openings are matched and set, which only the proper arrangement of the letters will accomplish; then the bolt and the knob C can be moved, but not otherwise. But before that knob and the bolt can be moved, the other knob D and its tumblers must be properly set, to allow its sub-bolt *p* to enter the recess or slot *o*, when the bolt can be moved; and a second, third, or more checks or locks like that, D, may be used, all of which must be exactly set before the bolt could be used or moved.

There is no spring to give, or yield, when "feeling" for the tumblers, or to indicate when they are free or have friction upon them.

The only indications of yielding, or "feeling," in my lock, are false ones, and mislead, instead of showing any-definite arrangement within.

The hubs of the tumblers *i* are furnished with openings *w*, which, though they admit the sub-bolt *p*, a short distance, do not allow it to pass through, the hole in one partially closing that in the other, and the bolt can only move when the opening *x* in the tumblers comes fairly and squarely in line with the sub-bolt *p*.

The shanks have shouldered recesses, which fit into similar recesses in the back-plate *c*, and then, when properly fastening by nuts which cannot be turned from the exterior, the knobs can neither be driven through nor drawn out, or the lock easily damaged or disarranged.

Having thus fully described my invention, What I claim therein as new, and desire to secure by Letters Patent, is—

1. The combination of the plates *a b c*, of which *a c* are the lock-plates, and *b* is the bolt, for constituting a lock, which may serve as a door also, when said bolt is arranged to occupy the entire space between the outer plates, to resist the introduction of powder, substantially as described.

2. Also, in combination with the side-plates and the bolt occupying the entire space between said plates, the openings *r s t t'* in said bolt, as herein explained, the two knobs and their shanks and tumblers, each forming a locking and unlocking-mechanism, in connection with the sliding bolt, one of said knobs turning and sliding, the other turning only, as and for the purpose substantially as described.

3. Also, in combination with the plates, bolt, and knobs, or their shanks, constructed and arranged as herein described, the tumblers *h*, composed of the hubs *i* and flanges *j*, and their openings, *x w l*, real and false, substantially as and for the purpose described.

4. Also, in combination, the cheek-plates *a c* and the bolt *b*, capable of fitting and filling the space, and sliding between them, the knobs and shanks acting both as knobs and keys, tumblers, in which there are real and false openings, *x w l*, and set by permutation, the whole being arranged as and for constituting a vault or safe-lock without springs, or a removable key, substantially as described.

DANIEL SNELL.
